Atty.

UNITED STATES PATENT OFFICE.

LESTER P. BARLOW, OF DETROIT, MICHIGAN.

ENGINE-COOLING SYSTEM.

Application filed January 3, 1927. Serial No. 158,514.

This invention relates to improvements in steam or vapor cooling for internal combustion engines of the automotive and other types.

5 One object of my invention is to prevent the hot liquids in the active portions of the system from passing through or intermingling with the liquids in the reserve supply, and thus keep the liquids in the supply cool 10 at all times regardless of the speed of or the load on the engine.

Another object of my invention is to provide the supply conduit from the pump to the cylinder jacket with a continuing portion 15 which extends above the normal liquid level for the jacket before entering the jacket so that the latter will be prevented from emptying or draining through the pump when the latter stops.

20 The invention consists further in the matters hereinafter described and claimed.

In the accompanying drawings—

Fig. 1 is a view of an internal combustion engine equipped with a cooling system 25 embodying the features of my invention; and

Fig. 2 is a vertical sectional view through the check valve to be hereinafter referred to.

In the drawing, 1 indicates an internal 30 combustion engine of the automotive type having a water jacket 2 about the cylinders of the engine, as in engines of this general type. The head 3 of the cylinder block is provided with an upwardly extending portion 35 forming a steam dome 4 opening into the jacket and adapted to have the cooling water rise therein from the jacket to the level *a*.

Located in front of the engine is a condenser 5, which may be made like the customary automobile radiator with its upper and lower tanks or headers 6, 7 and interposed core structure 8, through which currents of air pass in the motion of the car 45 and by the use of a fan 9, as in automotive design. A conduit 10 connects the dome 4 with the upper tank 6 of the condenser for conveying steam thereto, the steam being condensed as it passes down through the core 8 so as to be returned as condensate to the cooling system of the engine. The lower tank 7 has a vent 11 to the atmosphere so

that air may escape from the condenser as steam enters the same.

Disposed below the condenser 5 is a tank 55 or reservoir 12 of a size to contain a relatively large body of water as a supply and reserve for the system. The tank 12 has a filling neck 13, the cap of which has an opening 14 for venting the tank at all times to 60 the atmosphere. The maximum level of the water in the tank 12 is indicated by the dotted line *b*, and it is to be noted that this is below the bottom of the condenser.

A chamber 15 is disposed adjacent the 65 reservoir 12, and both are connected through the bottom walls thereof by a conduit 16, in which is a non-returnable means in the form of a check valve 17 arranged to prevent a back flow of water from the chamber 15 to 70 the tank 12. A conduit 18 connects the lower header 7 of the condenser 5 with the chamber 15 for conveying condensate thereto.

Located in the chamber 15 is a force pump 75 19, which may be connected with one of the moving parts of the engine so as to be driven thereby, although an independent drive may be employed if desired. The intake of the pump 19 preferably faces the bottom of the 80 chamber 15 and is located close to the same so as to be submerged in water at all times and thus insure a supply for the pump. A pipe 20 is connected with the discharge of the pump, and this pipe extends upward out 85 of the tank to above the level *a* to be maintained for the jacket 2. There the pipe 20 is connected by a bend 21 with a similar pipe 22, which extends downward along the outside of the jacket 2 and is connected into 90 the lower portion of the jacket, as at 23, for supplying water thereto when the pump is in operation. A pipe 24 connects the highest point of the conduit provided by the pipes 20, 22, as at the bend 21, with the 95 steam space in dome 4 to break the suction effect in this conduit and thus prevent the jacket 2 from siphoning back into the chamber 15 and connected pipes through the pump when the latter stops.

100 A conduit 25 connects the upper portion of the jacket 2 with the lower portion of the chamber 15 so as to allow the excess liquids supplied to the jacket through the

conduit 20—22 to return to said chamber. The conduit 25 connects with the dome 4 at the water level *a* therein so as to maintain said level for the jacket and thus prevent 5 lowering of the water in the jacket to allow the engine cylinders to overheat. The conduit 25 is sufficiently large in diameter to offer as little resistance as possible to the return flow of liquids to the chamber 15.

10 In having the condensate from the condenser 5 and the overflow waters from the jacket 2 both flow to the pump 13 through the chamber 15, these hot liquids do not pass through the supply tank 12, and thus do not 15 raise the temperature of the liquid content of said tank. This is an important feature in connection with steam cooling systems, as the supply water is kept cool and not heated to lose its cooling effect as when the hot condensate and overflow waters are required to 20 reach the pump through the supply tank. By use of the non-return check valve 17 in the connection between tank 12 and chamber 15, the hot liquids contained in and passing 25 through the latter can not enter the tank 12 to mingle with the cooling water therein to heat the same. This further aids in keeping the liquid content of the supply reservoir cool. By the entire arrangement, the 30 high temperatures in the active portion of the system are not allowed to raise the temperature of the cooling waters in the inactive portion of the system, and as a result the liquids in the reserve supply always 35 remain cool regardless of the speed of or load on the engine.

The details of structure and specific arrangement of parts shown and described 40 may be variously changed and modified without departing from the spirit and scope of my invention.

I claim as my invention:

1. In a vapor cooling system for internal combustion engines, the combination with a 45 cylinder jacket having a steam space above the same, of a condenser connected to said space to receive steam therefrom, a chamber to receive the condensate from said condenser and the overflow liquids from said jacket, a pump for forcing liquids from the chamber to said jacket, a reservoir disposed out of the path of hot liquids circulated by the pump and containing a supply of reserve 50 cooling liquid for the system, a connection from the reservoir to the chamber for supplying reserve cooling liquids thereto, and a non-returnable means in said connection.

2. In an internal combustion engine 60 vapor cooling system which is open continuously to the atmosphere and operating at all times at atmospheric pressure, the combination with a cylinder jacket, of means for supplying cooling liquids to said jacket including a force pump and a conduit connect- 65 ing the discharge of the pump to the lower

portion of the jacket, said conduit having a continuing portion extending above the normal level for the liquids in the jacket so as to prevent emptying of the jacket through 70 said conduit when the pump stops, and a return connection between the jacket and the pump.

3. In an internal combustion engine vapor cooling system which is open continuously to the atmosphere and operating at all times 75 at atmospheric pressure, the combination with a cylinder jacket, of means for supplying cooling liquids to said jacket including a force pump and a conduit connecting the discharge of the pump to the lower portion 80 of the jacket, said conduit having a continuing portion extending above the normal level for the liquids in the jacket so as to prevent emptying of the jacket through said conduit when the pump stops, means to 85 break the suction effect in the conduit, and a return connection between the jacket and the pump.

4. In an internal combustion engine vapor cooling system which is open continuously 90 to the atmosphere and operating at all times at atmospheric pressure, the combination with a cylinder jacket, of means for supplying cooling liquids to said jacket including a force pump and a conduit connecting the discharge of the pump to the lower portion 95 of the jacket, said conduit having a continuing portion extending above the normal level for the liquids in the jacket so as to prevent emptying of the jacket through said conduit when the pump stops, a return connection between the jacket and the pump, a reservoir disposed out of the path of hot liquids circulated by the pump containing a 100 reserve supply of cooling liquids therefor, said reservoir being connected with the intake of the pump, and a non-returnable 105 means in said connection.

5. In a vapor cooling system for internal combustion engines, a circuit containing hot 110 liquids of the active cooling portions of the system, a force pump to circulate the liquids through the circuit, a reservoir disposed out of said circuit and containing a reserve supply of cooling liquid therefor, a connection 115 from the reservoir to the circuit, and a non-returnable means in said connection.

6. In a vapor cooling system for internal combustion engines, the combination with a cylinder jacket having a steam space above 120 the same, of a condenser connected to said space to receive steam therefrom, means providing a circuit for the hot liquids of the system and connected with the jacket for 125 supplying liquids thereto, means for conveying the condensate from the condenser to said circuit, a reservoir vented to the atmosphere and containing a reserve supply of cooling liquid for the system, said reservoir being disposed out of said circuit so that 130

none of the hot liquids of the system pass through the reservoir, a connection from the reservoir to the circuit for supplying reserve cooling liquids thereto, and non-returnable means in said connection.

7. In a vapor cooling system for internal combustion engines, the combination with a cylinder jacket having a steam space above the same, of a condenser connected to said space to receive steam therefrom, a chamber connected to the condenser to receive condensate therefrom, means including a force pump to supply liquids to the jacket from said chamber, a reservoir vented to the atmosphere and containing a reserve supply of cooling liquid for the system, said reservoir being disposed out of the path of the circuit through said chamber so that none of the hot liquids of the system pass through the reservoir, a connection from the reservoir to the chamber for supplying the cooling liquids to the system through said chamber, and a non-returnable means in said connection.

25 8. In an internal combustion engine vapor cooling system which is open continuously to the atmosphere and operates at all times at atmospheric pressure, the combination with a cylinder jacket having a steam space above the same, of a force pump below the jacket, supply and overflow conduits connected with the discharge and intake sides, respectively of the pump, said overflow conduit opening

into the jacket at approximately the normal liquid level to be maintained in the jacket, 35 said supply conduit opening into the jacket below said level and having a continuing portion extending above said level, and a vent connection from the portion of the conduit above said level to said steam space. 40

9. In an internal combustion engine vapor cooling system which is open continuously to the atmosphere and operating at all times at atmospheric pressure, the combination with a cylinder jacket having a 45 steam space above the same, of a condenser connected with said space to receive steam therefrom, a chamber located below the jacket and the condenser and connected with the latter to receive condensate therefrom, a 50 pump having its intake disposed to draw liquids from said chamber, an overflow conduit connecting said chamber with said jacket with the opening of the conduit into the jacket at approximately the normal 55 liquid level to be maintained in the jacket, a supply conduit connected with the discharge of the pump and extending above the normal liquid level for the jacket and thence back to and connected with the lower portion of the jacket below said level, and means venting the portion of the conduit above said level to said steam space.

In testimony whereof I affix my signature this 27th day of December, 1926.

LESTER P. BARLOW.
